UNITED STATES PATENT OFFICE.

FREDERICK E. DORR, OF EVERETT, MASSACHUSETTS.

DESIGN FOR A GAME-BOARD.

48,488.

Specification for Design.

Patented Feb. 1, 1916.

Application filed October 30, 1914. Serial No. 869,490. Term of patent 14 years.

To all whom it may concern:

Be it known that I, FREDERICK E. DORR, a citizen of the United States, residing at Everett, in the county of Middlesex and State of Massachusetts, have invented a new, original, and ornamental Design for Game-Boards, of which the following is a specification, reference being had to the accompanying drawing, forming a part thereof.

The figure of the drawing is a plan view

of a game-board, showing my new design, which is pictorially applied to the flat surface of the board in any suitable manner, with parts shown in colors if desired.

I claim:

The ornamental design for a game-board, substantially as shown and described.

FREDERICK E. DORR.
